US0D1102610S

(12) **United States Design Patent** (10) **Patent No.:** **US D1,102,610 S**
(45) **Date of Patent:** **** Nov. 18, 2025**

(54) **ELECTROSTIMULATION APPARATUS**

(71) Applicant: **FESIA TECHNOLOGY, S.L.**,
Donostia-San Sebastian (ES)

(72) Inventor: **Haritz Zabaleta**, Donostia-San
Sebastian (ES)

(73) Assignee: **FESIA TECHNOLOGY, S.L.**,
Donostia-San Sebastian (ES)

(**) Term: **15 Years**

(21) Appl. No.: **29/775,219**

(22) Filed: **Mar. 22, 2021**

(30) **Foreign Application Priority Data**

(57) **CLAIM**

The ornamental design for the electrostimulation apparatus, as shown and described.

DESCRIPTION

FIG. 1 is a front perspective view in a position of use of an electrostimulation apparatus;

FIG. 2 is a top plan view thereof;

FIG. 3 is a bottom plan view thereof;

FIG. 4 is a top side perspective view thereof;

FIG. 5 is a bottom side perspective view thereof;

FIG. 6 is a left side perspective view thereof; and,

FIG. 7 is a right side perspective view thereof.
